DISCONNECT SWITCH

Paul R. Pierson, Pittsburgh, Pa., assignor to Westinghouse Electric Corporation, East Pittsburgh, Pa., a corporation of Pennsylvania

Application May 28, 1947, Serial No. 751,161

8 Claims. (Cl. 200—5)

1

My invention relates, generally, to disconnect switches and, more particularly, to mechanisms for operating disconnect switches of the type utilized in metal-enclosed switchgear.

Many electric power companies require that provision be made for grounding certain power circuits through a device which can be electrically controlled from a remote location. Frequently the circuit breaker which controls the energization of a power circuit is also utilized as the grounding device and the isolating disconnect switches are utilized to set up the grounding circuit. For this service the disconnect switches usually have been operated individually.

An object of my invention, generally stated, is to provide a disconnect switch operating mechanism which shall be simple and efficient in operation and which may be economically manufactured and installed.

A more specific object of my invention is to provide for operating a plurality of disconnect switches either jointly or individually.

Another object of my invention is to provide for selectively locking certain ones of groups of gang-operated disconnect switches in preselected positions without interfering with the operation of other switches of the group.

Other objects of my invention will be explained fully hereinafter or will be apparent to those skilled in the art.

In accordance with one embodiment of my invention, the disconnect switches on either side of a circuit breaker may be utilized for grounding purposes. The switches are gang-operated by a main shaft and two secondary shafts which are driven by the main shaft through levers and tie rods. Each secondary shaft operates a group of switches and may be locked to the main shaft or locked in either the "open" or the "closed" position of its switches. The circuits connected to the switches may be grounded through the circuit breaker and the proper switches.

For a better understanding of the nature and objects of my invention, reference may be had to the following detailed description, taken in conjunction with the accompanying drawings, in which:

Figure 1 is a view, in side elevation, of a portion of a switchgear structure embodying the principal features of my invention;

Fig. 2 is a view, in rear elevation, of the structure shown in Fig. 1, and

Figs. 3 and 4 are enlarged detail views taken along the lines III—III and IV—IV, respectively, of Fig. 2.

Referring to the drawings, and particularly to Fig. 1, the structure shown therein comprises two groups of disconnect switches 10 and 11 which are disposed in a housing 12, only a portion of which is shown. The disconnect switches of group 10 may be of the usual type, each switch comprising a blade 13 which is hinged on a fixed terminal 14 and engages another fixed terminal 15 when in the closed position. The disconnect switches of group 11 are similar to those of group 10, each switch comprising a blade 16 which is hinged on a terminal 17 and engages another terminal 18 when closed.

As shown, the terminals of the disconnect switches are mounted on insulators 19, which, in turn, are mounted in the housing 12. The hinge terminals 14 and 17 may be connected to opposite terminals of a circuit breaker (not shown). The fixed terminals 15 and 18 may be connected to power conductors through which a circuit may be established by closing the circuit breaker when the switch blades are closed, as shown in the drawings. When the switch blades are open, the circuit breaker is isolated from the power conductors.

As explained hereinbefore, it is sometimes desirable to utilize the circuit breaker and the disconnect switches as a means for grounding one or the other of the power circuits to which the disconnect switch terminals are connected. In order to accomplish this result, grounding contact members 21 are disposed to be engaged by the switch blades 13 when they are in the fully opened position. Likewise, grounding contact members 22 are disposed to be engaged by the switch blades 16 when they are in the fully opened position. The contact members 21 and 22 may be grounded through the housing structure or ground bus in the usual manner.

As shown in Fig. 2, the switch group 10 may comprise a plurality of disconnect switches. Thus, in a three-phase power system, the group 10 would contain at least three individual switches, there being one for each phase. Likewise, the group 11 would contain at least three individual switches. In order to simplify the drawings, only two switches have been shown in each group.

In order to simplify the operation of the switches when it is desired merely to isolate the circuit breaker from the power conductors, all of the switch blades 13 of group 10 are connected to a secondary shaft 23 which is rotatably mounted in the housing 12 in suitable bearings 24. Likewise, all of the switch blades 16 of group

11 are connected to a secondary shaft 25 which is mounted in suitable bearings 26. The switch blades are connected to their respective shafts by levers 27 and insulators 28.

The secondary shaft 23 is connected to a main shaft 29 by means of a tie-rod 31 and levers 32, 33 and 34 and a bolt 35. Likewise, the secondary shaft 25 is connected to the main shaft 29 by means of a tie-rod 36 and levers 31, 38 and 39 and a bolt 41. The levers 33 and 38 are rotatably mounted on the shaft 29. The levers 34 and 39 are secured to the shaft 29. The lever 34 may be connected to the lever 33 by the bolt 35. Likewise, the lever 39 may be connected to the lever 38 by the bolt 41. The shaft 29 may be rotated by a gear mechanism 42 which may be operated by a crank 43, see Fig. 1. In this manner the shaft 29 may be rotated to open and close both groups of disconnect switches in the usual manner.

In order that the circuit breaker and the disconnect switches may be utilized for grounding one or the other of the power circuits connected to the disconnect switches, provision is made for locking either group of switches in a predetermined position without interfering with the operation of the other group of switches. Thus, if it is desired to ground the power conductors connected to the switches of group 10 the grounding operation can be performed in two ways. The switches of group 10 may be locked in the closed position by removing the bolt 35 from the position shown by the full lines in Figs. 2 and 3, and inserting it through the lever 33 into a block 44 which is secured to the housing 12. The removal of the bolt 35 from its position shown by the full lines and inserting it in the position shown by the dotted lines, releases the lever 33 from the lever 34 and secures the lever 33 to the block 44, thereby retaining the switches of group 10 in the closed position. The shaft 29 may then be rotated to open the switches of group 11 and cause them to engage the grounding contact members 22.

If desired, the switches of group 11 may be locked in the grounded position by removing the bolt 41 from the position shown by the full lines in Figs. 2 and 4 and inserting it through the plate 38 into a block 45 which is secured to the housing 12. In this manner the lever 38 is released from the lever 39 and is secured to the block 45 to retain the switches of group 11 in the grounded position.

The circuit breaker may then be closed, thereby grounding the power conductors connected to the switches of group 10. Furthermore, neither group of switches can be inadvertently operated to remove the ground while the circuit breaker is closed since both groups are locked in the desired position.

If it is desired to ground the power conductors connected to the switches of group 11, the switches of group 11 are locked in the closed position by inserting the bolt 41 through the lever 38 into a block 46 which is secured to the housing 12. The switches of group 10 are then operated to the grounded position by rotating the shaft 29 and they may be locked in the grounded position by inserting the bolt 35 through the plate 33 into a block 47 which is secured to the housing 12 as shown in Fig. 3.

In this manner, either group of switches may be locked in one or the other of two predetermined positions without interfering with the operation of the other group of switches. Fur-

thermore, both groups may be released from the operating mechanism and locked in one or the other of two predetermined positions.

As previously explained, the grounding operation may be performed in another way. Thus, if it is desired to ground the circuits connected to the switches of group 10, both groups of switches are opened, as a six pole gang, under proper interlock protection to insure that the associated circuit breaker is open. The six poles engage the grounding contact members in the open position. The switches of group 11 are then locked in the grounded position with the bolt 41 and the switches of group 10 are returned to the closed position, thereby completing the circuit to the terminals of the circuit breaker. The grounding of this circuit can then be accomplished by closing the circuit breaker.

If it is desired to ground the circuits connected to the switches of group 11 the operation is similar to the foregoing except that the switches of group 10 are locked in the grounded position with the bolt 35 and the switches of group 11 are returned to the closed position. The circuits are then grounded by closing the circuit breaker.

From the foregoing description it is apparent that I have provided a mechanism for operating two groups of disconnect switches when it is desired to operate both groups simultaneously. If it is desired to operate one group independently of the other, this may be readily done with the mechanism herein described.

Furthermore, either group may be locked in one or the other of two predetermined positions without interfering with the operation of the other group. As explained hereinbefore, the present structure is particularly suitable for operating disconnect switches which are utilized in conjunction with an automatically controlled circuit breaker for grounding the power circuits connected to the disconnect switches.

Since numerous changes may be made in the above-described construction, and different embodiments of the invention may be made without departing from the spirit and scope thereof, it is intended that all matter contained in the foregoing description or shown in the accompanying drawing shall be interpreted as illustrative and not in a limiting sense.

I claim as my invention:

1. In a switchgear structure, in combination, a plurality of disconnect switches, a main shaft, crank means for rotating said shaft, a plurality of actuating means for opening and closing said switches, lever means for selectively connecting said actuating means to said main shaft to operate preselected switches independently of the other switches, and bolt means cooperating with said lever means for selectively locking said switches in predetermined positions.

2. In a switchgear structure, in combination, a plurality of disconnect switches, a main shaft, crank means for rotating said shaft, a plurality of actuating means for opening and closing said switches, lever means for selectively connecting said actuating means to said main shaft to operate preselected switches independently of the other switches, and bolt means cooperating with said lever means for selectively locking said switches in predetermined positions without interfering with the operation of the other switches.

3. In a switchgear structure, in combination, a plurality of disconnect switches, a main shaft, crank means for rotating said shaft, a plurality of actuating means for opening and closing said

switches, lever means for selectively connecting said actuating means to said main shaft to operate preselected switches independently of the other switches, and bolt means cooperating with said lever means for selectively locking said actuating means to retain preselected switches in predetermined positions.

4. In a switchgear structure, in combination, a plurality of disconnect switches, a main shaft, crank means for rotating said shaft, a plurality of actuating means for opening and closing said switches, lever means for selectively connecting said actuating means to said main shaft to operate preselected switches independently of the other switches, and bolt means cooperating with said lever means for selectively locking said actuating means to retain preselected switches in predetermined positions without interfering with the operation of the actuating means for the other switches.

5. In a switchgear structure, in combination, a plurality of groups of disconnect switches, a main shaft, gear means for rotating said shaft, a secondary shaft for actuating each group of switches, lever means for selectively connecting said secondary shafts to said main shaft to operate a preselected group of switches independently of the other switches, and bolt means cooperating with said lever means for selectively locking groups of said switches in predetermined positions.

6. In a switchgear structure, in combination, a plurality of groups of disconnect switches, a main shaft, gear means for rotating said shaft, a secondary shaft for actuating each group of switches, lever means for selectively connecting said secondary shafts to said main shaft to operate a preselected group of switches independently of the other switches, and bolt means co-

operating with said lever means for locking a preselected group of switches in a predetermined position without interfering with the operation of the other switches.

5 7. In a switchgear structure, in combination, a plurality of groups of disconnect switches, a main shaft, gear means for rotating said shaft, a secondary shaft for actuating each group of switches, lever means for selectively connecting 10 said secondary shafts to said main shaft to operate a preselected group of switches independently of the other switches, and bolt means cooperating with said lever means for selectively locking each secondary shaft against rotation to retain its group of switches in a predetermined position.

10 8. In a switchgear structure, in combination, a plurality of groups of disconnect switches, a main shaft, gear means for rotating said shaft, a secondary shaft for actuating each group of switches, lever means for selectively connecting said secondary shafts to said main shaft to operate a preselected group of switches independently of the other switches, and bolt means for selectively locking the connecting means for each secondary shaft in a predetermined position to retain the switches operated by said shaft in a preselected position without interfering with the operation of the other switches.
